(57) **CLAIM**

The ornamental design for a light support mount, as shown and described.

DESCRIPTION

FIG. 1 is a front view of a light support mount showing my new design;

FIG. 2 is a rear view of the light support mount;

FIG. 3 is a left side view of the light support mount;

FIG. 4 is a right side view of the light support mount;

FIG. 5 is a top view of the light support mount;

FIG. 6 is a bottom view of the light support mount; and,

FIG. 7 is a top front side perspective view of the light support mount.

The broken lines are illustrative of portions of the light support mount forming no part of the claimed design.
